(57) **CLAIM**

The ornamental design for a backpack accessible garment as shown and described.

DESCRIPTION

FIG. 1 is a front elevational view of a backpack accessible garment showing my new design;

FIG. 2 is a rear elevational view thereof;

FIG. 3 is a rear left perspective view thereof; and,

FIG. 4 is the perspective view of FIG. 3 shown in use with a backpack.

The dashed lines throughout the figures are environmental structures and form no part of the claimed design.
